LAMP BASE

Suzanne M. Schieber, Chicago, Ill.

Application November 3, 1954, Serial No. 32,946

Term of patent 14 years

(Cl. D48—20)

FIG. 1

Des. 174,474

PAGE 2

FIG. 2

To all whom it may concern:

Be it known that I, Suzanne M. Schieber, a citizen of the United States of America, residing at Chicago, in the county of Cook and State of Illinois, have invented a new, original, and ornamental Design for Lamp Base, of which the following is a specification, reference being had to the accompanying drawings, forming part thereof.

Fig. 1 is a front perspective view of a lamp base showing my new design.

Fig. 2 is a rear perspective view thereof.

Fig. 3 is a side elevation.

I claim:

The ornamental design for a lamp base, as shown.
